UNITED STATES PATENT OFFICE.

RICHARD W. CONE, OF BOSTON, MASSACHUSETTS.

BOOT AND SHOE.

SPECIFICATION forming part of Letters Patent No. 240,890, dated May 3, 1881.

Application filed March 21, 1881. (Model.)

To all whom it may concern:

Be it known that I, RICHARD W. CONE, of Boston, county of Suffolk, State of Massachusetts, have invented a new and useful Improvement 5 in Boots and Shoes, of which the following description, in connection with the accompanying drawings, is a specification.

This invention in boots and shoes has for its object improvements in the counter and 10 counter-lining and the method of manipulating them during lasting, whereby the correct insertion of the metal or other flanged heel-stiffening between the counter-lining and counter lower end of the back or quarter of the 15 boot or shoe is facilitated.

In the manufacture of boots the counter or lower end of the boot-leg inside has a counter-lining stitched to it by a seam extended across the back, and the stiffening is inserted in the 20 space between them. When a flanged or other stiffening is inserted into the space between the counter-lining and counter before the boot is applied to the last, as has been commonly done, much difficulty has been experienced in 25 securing the counter-lining to the inner sole, and during the operation of lasting the heel it has been difficult to keep the stiffening correctly in place and secure the counter evenly to the inner sole, so as to assure uniformity in 30 the stiffened parts of the boot about the heel of the last. In accordance with my invention I cut or shape the lower edge of the counter-lining, which is sewed to the counter, so as to form a series of lips, which, when the boot is 35 subsequently placed on the last, are laid over separately on the heel end of the inner sole, where the lips are secured evenly by tacks or pegs. Securing the lips of the counter-lining to the inner sole separates the lower end of the 40 counter-lining from the lower end of the counter or boot-back, forming a space, into which the stiffening, flanged or simply curved and in one or two pieces, may be easily inserted and crowded to place without affecting the 45 correct relative position of the counter and inner sole, for, being connected together, the one cannot move on the other under the strain of inserting the stiffening. This my method is especially advantageous when using a flanged 50 metal fastening such as described in United States Patent No. 197,696, November 27, 1877.

Figure 1 represents the inner side of a boot-leg with the counter-lining sewed to it; Fig. 2, a view of part of the boot applied to the inner sole, with the lips of the counter-lining turned over upon and secured to the inner sole; Fig. 3, a similar view, with one-half of a stiffener inserted between the counter-lining and back or counter of the boot; and Fig. 4 shows one-half of a flanged metal stiffening removed from the boot.

The front of the boot and the back *a* and inner sole, *b*, are all as usual. The counter-lining *c* has its upper edge sewed to the back *a*, as commonly done, and the ends of the counter are connected in the side seams, or caught and covered by the saddle or other seam-forming parts. I cut or shape the lower end of the counter-lining, as shown in Fig. 1, to form a series of lips, *d*, which, after the boot is placed 70 upon the last, in connection with the inner sole, *b*, as usual, are bent over upon and secured separately to the inner sole by nails or pegs or fastenings 2. Fastening the lips *d* to the inner sole in this way enables the boot-maker 75 to insure the correct relative positions of the boot-back and inner sole to produce a uniform heel, and leaves the counter-lining turned in and the lower end of the counter standing or separated from the lining, so that the stiffener 80 *e* (flanged or otherwise) may be readily inserted and pushed or driven down in position between the counter and lining without liability of disturbing the correct relative position of the said parts with relation to the inner sole. The stiffening, whether of two short pieces or of one 85 long piece, having been inserted between the counter and lining, the lower end of the back is then turned over upon the flanged part of the stiffening, and is secured in the usual way, 90 when the outer sole—the fore part and shank of the boot having been lasted to the inner sole, as usual—may be applied and secured in the usual manner.

I claim—

1. The back or counter and inner sole combined, with the counter-lining sewed thereto, and shaped at its lower end to form lips that are secured to the inner sole by independent fastenings, which extend only through the lips 100 and inner sole, substantially as described.

2. In the art or method of manufacturing

boots and shoes, the following steps, viz: providing the counter-lining, which is sewed to the counter *a*, with a series of lips, securing the said lips to the inner sole by independent fastenings, inserting or forcing the stiffening into place between the counter and counter-lining while the counter is secured to the inner sole by the said fastenings, and then turning over the lower end of the back to extend over the inner sole and stiffening, preparatory to apply-

ing the outer sole, all substantially as described.

In testimony whereof I have signed my name to this specification in the presence of two subscribing witnesses.

RICHARD W. CONE.
